UNITED STATES PATENT OFFICE.

CHARLES W. TREMPER, OF NEW HAVEN, CONNECTICUT, ASSIGNOR TO THE TREMPER-SHIELDS CO., OF NEW HAVEN, CONNECTICUT, A CORPORATION.

AIR-CONTROL DEVICE FOR AIR-OPERATED SHEET-FEEDING MECHANISMS.

Application filed July 7, 1927. Serial No. 203,971.

My invention relates to an improved air-control device for air-operated sheet-feeding mechanisms, the object being to produce, for the purpose described, a mechanism of superior simplicity, compactness, accessibility for repair and adjustment, responsiveness in action, adaptability to compensate for wear, and distinguished in particular by its construction so as to leave the main air-pipe sealed to the atmosphere while opening the extension air-pipe thereto.

With these ends in view, my invention consists in an air-control device for air-operated sheet-feeding mechanisms characterized by its adaptation to leave the main air-pipe closed to the atmosphere when the extension air-pipe is opened thereto, whereby normal pressures in the main air-pipe are maintained under all operating conditions.

My invention further consists in a device of the character described, constructed and adapted so that it can be cut out of operation only at one point and that at the completion of any one cycle of its operation.

My invention further consists in a device characterized as above described, the valve-members of which have plane co-operating faces provided with air-ports brought into and out of registration by the movement of one of the said valve-members with respect to the other.

My invention further consists in a mechanism characterized as described and having certain other details of construction and combinations of parts as will be hereinafter described and pointed out in the claims.

In the accompanying drawings:

Fig. 1 is a broken face view of my improved mechanism in position to seal the main air-pipe to the atmosphere and open the extension air-pipe thereto;

Fig. 2 is a broken view in horizontal section on the line 2—2 of Fig. 1;

Fig. 3 is a broken view in inside end elevation of the mechanism with the driving- and rock-shafts in section;

Fig. 4 is a broken plan view of the mechanism;

Fig. 5 is a view corresponding to Fig. 3 but showing the detent and latch co-acting to hold the mechanism out of play;

Fig. 6 is a view corresponding to but less comprehensive than Fig. 1, showing the

mechanism cut out of play, as in the preceding figure;

Fig. 7 is a face view, corresponding to Fig. 1 but showing the oscillating valve-plate in the position in which its air-port is registered with the air-port of the fixed valve-plate;

Fig. 8 is a sectional view on the line 8—8 of Fig. 7;

Fig. 9 is a view in vertical section on the line 9—9 of Fig. 7; and

Fig. 10 is a diagrammatic view of the layout of a sheet-feeding mechanism, including four unit-mechanisms constructed in accordance with my invention, two of them being installed for vacuum-control and two of them for compressed-air control.

In carrying out my invention, as herein shown, I employ a vertically-arranged stationary extension-line valve-member 15 having a flat offsetting bearing-surface 16, this member being provided with bosses 17 and 18 respectively receiving a rock-shaft 19 and a drive-shaft 20, by which the said valve-member 15 is supported in the machine-frame 21. The said valve-member is provided with an extension-line air-port 22 elongated in the vertical plane and opening into a threaded socket 23 in a boss 24 of the said member, the said socket receiving the threaded inner end of a coupling-nipple 25 projecting outwardly from it and, in turn, receiving a flexible air-pipe 26 forming what I will term, for convenience, the "extension-pipe" of my improved device. The bearing-surface 16 aforesaid is laterally extended in its plane to form a seal 16^a, the purpose of which will be hereafter explained.

The said air-port 22 co-acts with a corresponding vertically-elongated main-line air-port 27 formed in an oscillating main-line valve-member 28 having a flat offsetting bearing-surface 29 which rides directly upon the bearing-surface 16 and seal 16^a of the fixed valve-member 15 already described. The air-port 27 opens into a threaded socket 30 in a boss 31 offsetting from the oscillating valve-member 28, the said socket 30 receiving the threaded inner end of a coupling-nipple 32, the projecting outer end of which receives the main air-pipe 33. The said oscillating valve-member 28 has a bearing-hub 34 receiving a stud 35 mounted in the fixed

valve-member 15, in which it is secured by a nut 36. The stud 35 projects beyond the hub 34 for the reception of a helical spring 37, retained on the said stud by a nut 38 and exerting a constant effort to maintain the flat bearing-surfaces 16, 16^a and 29 in air-tight contact.

The oscillating valve-member 28 is provided with a depending operating-arm 39 mounting a pin 40 carrying a roller 41 co-acting with the cam-face 42 of a cup-shaped cam 43 having a hub 44 coupled by a key 45 and a set-screw 46 to the drive-shaft 20. The said oscillating valve-member 28 is also provided with a laterally-extending arm 49 providing for the attachment of the lower end of a helical operating-spring 50, the upper end of which is secured to a stud 51 in the fixed valve-member 15, the said spring exerting a constant effort to swing the oscillating valve-member 28 into position for the registration of the air-ports 22 and 27 and to maintain the roller 41 in engagement with the cam-face 42 of the cam 43.

For the purpose of holding the oscillating valve-member 28 in its cut-out position, in which its air-port 27 is out of registration with the air-port 22, so as to seal the main air-pipe 33 to the atmosphere and open the extension air-pipe 26 thereto, I employ a pivotal latch 52 formed at its outer end with a nose 53 and also formed with a hub 54, by means of which it is mounted so as to rock upon a stud 55 in the oscillating valve-member 28, with which latter it has bodily movement. The opposite end of the said latch 52 is furnished with an arm 56 provided for the attachment of a helical latch-operating spring 57, the lower end of which is secured to a pin 58 offsetting from the hub 34 of the oscillating valve-member 28. The spring 57 normally tends to lift the nose 53 of the latch 52 to the limit of the upward movement thereof, which is determined by a stop-pin 59 mounted in the valve-member 28 and located therein in position to be engaged by the lower edge of the said arm 56. The nose 53 of the latch 52 has its upper face beveled as at 60, whereby it is adapted to ride under a detent-arm 61 extending outward from a hub 62 secured by means of a set-screw 63 to the rock-shaft 19, which is furnished with an upstanding operating-arm 64 secured to it by a pin 65 and constructed at its upper end with a fork 66 receiving a pin 67, by means of which the arm 64 is connected with a horizontally-arranged pull-rod 68 carrying a ball-handle 69, as particularly shown in Fig. 5, whereby the detent-arm 61 is manually moved into the path of the latch 52, which reciprocates in substantially a horizontal plane with the oscillation of the valve-member 28.

To limit the rocking movement of the rock-shaft 19 and hence of the detent-arm

61, the said shaft is provided at its outer end with a hub 70 secured by a set-screw 71 to the said shaft and having corresponding depending bowed stop-arms 72-72 which alternately engage with the opposite sides of the hub 73 of a drive-gear 74 on the outer end of the drive-shaft 20.

Fig. 10 is a diagrammatic illustration of an air-operated air-controlled sheet-feeding system in which the air is controlled by unitary devices like the device already described, it being understood that this diagram is an illustration of one use of my invention.

In the diagram, an electric motor 75 is arranged to drive a vacuum-pump 76 and a pressure-pump 77, the former being connected by main air-pipes 33 with the oscillating valve-members 28 of two of my improved control-units A and B. The extension air-pipe 26 of unit A extends to a pair of vacuum-operated sheet-forwarding fingers 78, while the extension air-pipe 26 of unit B extends to a pair of vacuum-operated sheet-pick-up fingers 79.

The pressure-pump 77 aforesaid is connected by an air-pipe 80 with a pressure-tank 81 with which are connected the main air-pipes 33-33 of a pair of my improved control-units C and D, corresponding in construction and operation to the above-mentioned control-units A and B. The extension air-pipe 26 of unit C feeds compressed air to a pair of sheet-fluffing nozzles 82-82 of any approved construction and located on opposite edges of the sheet 83, while the extension air-pipe 26 of the unit D leads to a pair of compressed-air sheet-separating nozzles 84-84. As many of these control-units may be installed in any given system as its size and character may require, inasmuch as they are compact unitary structures.

In this connection, it is to be particularly noted that whether my improved air-control units are installed for the control of vacuum or compressed air, their main air-pipes are always sealed to the atmosphere when their extension air-pipes are open thereto, so that the vacuum or pressure, as the case may be, built up in the main air-pipe, is not depleted or lowered when the extension air-pipe is opened to the atmosphere.

I claim:

1. An air-control device for air-operated sheet-feeding mechanisms, comprising a main air-pipe, an extension air-pipe, a valve-member connected with the said main air-pipe, a valve-member connected with the said extension air-pipe, each of the said valve-members having an air-port, and one being movable with respect to the other, means for operating the movable valve-member for registering and de-registering the said air-ports, whereby the main air-pipe is sealed to the atmosphere and the exten-

5 sion air-pipe is opened thereto, and a de-
tent for holding the said movable valve-
member with its air-port out of registration
with the air-port of the other member, the
5 said detent operating only at one point and
that at the completion of any one cycle of
the operation of the device.

2. An air-control device for air-operated
10 sheet-feeding mechanisms, comprising a
main-line valve-member and a complemen-
tary co-acting extension-line valve-member,
one of which is movable with respect to the
other; a main-line port in the said main-line
15 valve-member and an extension-line port in
the said extension-line valve-member; a
main air-pipe and an extension air-pipe re-
spectively connected to the said main-line
port and the said extension-line port; a seal
20 for the said main-line port; yielding means
normally urging the movable valve-member
into position to register the said ports;
means for moving the said ports out of regis-
tration against the urge of the said yielding
25 means; whereby when the said ports are
moved out of registration, the said extension
air-pipe is open to the atmosphere and the
said main air-pipe is closed thereto by the
said seal; and a manually-operable latch-
30 ing-mechanism for holding the said ports
out of registration against the urge of the
said yielding means.

3. An air-control device for air-operated
35 sheet-feeding mechanisms, comprising a
main-line valve-member and a complemen-
tary co-acting extension-line valve-member,
one of which is movable with respect to the
other; a main-line port in the said main-line
40 valve-member and an extension-line port in
the said extension-line valve-member;
a main air-pipe and an extension air-pipe re-
spectively connected to the said main-line
port and the said extension-line port; a seal
45 for the said main-line port; yielding means
normally urging the movable valve-
member into position to register the said ports;
means for moving the said ports out of regis-
tration against the urge of the said yielding
50 means; whereby when the said ports are
moved out of registration, the said ex-
tension air-pipe is open to the atmosphere
and the said main air-pipe is closed thereto
by the said seal; and a manually-operable
55 latching-mechanism co-acting with the said
movable valve-member to hold the said ports
out of registration when the said movable
valve-member reaches the limit of its move-
ment in the direction of moving the said
ports out of registration.

4. An air-control device for air-operated
60 sheet-feeding mechanisms, comprising a
main-line valve-member and a complemen-
tary co-acting extension-line valve-member,
one of which is movable with respect to the
other; a main-line port in the said main-
65 line valve-member and an extension-line port

in the said extension-line valve-member; a
main air-pipe and an extension air-pipe re-
spectively connected to the said main-line
port and the said extension-line port; a seal
70 for the said main-line port; yielding means
normally urging the movable valve-member
into position to register the said ports;
means for moving the said ports out of regis-
tration against the urge of the said yielding
75 means; whereby when the said ports are
moved out of registration, the said ex-
tension air-pipe is open to the atmosphere
and the said main air-pipe is closed thereto
by the said seal; a latch carried by the move-
80 ble valve-member; and a manually-operable
detent co-acting with the said latch for hold-
ing the ports out of registration against the
counter-urge of the said yielding means.

5. An air-control device for air-operated
85 sheet-feeding mechanisms, comprising a
main-line valve-member and a complemen-
tary co-acting extension-line valve-member,
one of which is movable with respect to the
other; a main-line port in the said main-line
90 valve-member and an extension-line port in
the said extension-line valve-member; a
main air-pipe and an extension air-pipe re-
spectively connected to the said main-line
port and the said extension-line port; a seal
95 for the said main-line port; yielding means
normally urging the movable valve-member
into position to register the said ports;
means for moving the said ports out of regis-
tration against the urge of the said yielding
100 means; whereby when the said ports are
moved out of registration, the said ex-
tension air-pipe is open to the atmosphere
and the said main air-pipe is closed thereto
by the said seal; a spring-actuated pivotal
105 latch carried by the movable valve-member;
and a manually-operable pivotal detent co-
acting with the said latch for holding the
ports out of registration against the counter-
urge of the said yielding means.

6. An air-control device for air-operated
110 sheet-feeding mechanisms, comprising a
main-line valve-member and a complemen-
tary co-acting extension-line valve-member,
one of which has oscillating movement with
respect to the other; a spring for holding
115 the said valve-members in co-acting engage-
ment; a main-line port in the said main-line
valve-member and an extension-line port in
the said extension-line valve-member; a
main air-pipe and an extension air-pipe re-
120 spectively connected to the said main-line
port and the said extension-line port; a seal
for the said main-line port; means for oscil-
lating one of the said valve-members with
respect to the other for moving the said ports
125 into and out of registration; whereby when
the said ports are moved out of registration,
the said extension air-pipe is open to the at-
mosphere and the said main air-pipe is closed
thereto by the said seal.

7. An air-control device for air-operated sheet-feeding mechanisms, comprising a main-line valve-member and a complementary co-acting extension-line valve-member, 5 both of which are formed with co-acting flat valve-faces and one of which has sliding movement with respect to the other; a main-line port intersecting the flat face of the said main-line valve-member and an extension- 10 line port intersecting the flat face of the said extension-line valve-member; a main air-pipe and an extension air-pipe respectively connected to the said main-line port

and the said extension-line port; a seal for the said main-line port; and means for sliding one of the said valve-members with respect to the other for moving the said ports into and out of registration; whereby when the said ports are moved out of registration, the said extension air-pipe is open to the atmosphere and the said main air-pipe is closed thereto by the said seal. 15 20

In testimony whereof, I have signed this specification.

CHARLES W. TREMPER.
